UNITED STATES PATENT OFFICE.

CHARLES R. HARRIS, OF WILLIAMSPORT, PENNSYLVANIA.

DESIGN FOR A BUCKLE-FRONT.

SPECIFICATION forming part of Design No. 22,225, dated February 21, 1893.

Application filed December 10, 1892. Serial No. 454,787. Term of patent 7 years.

To all whom it may concern:

Be it known that I, CHARLES R. HARRIS, a citizen of the United States, residing at Williamsport, in the county of Lycoming and State of Pennsylvania, have invented and produced a new and original Design for Buckle-Fronts, of which the following is a specification, reference being had to the accompanying drawings, illustrating the same.

- o The leading feature of my design consists of a buckle front made to represent the bust of a woman with her hands raised in the act of holding a fan behind her head.

A represents the bust of a woman whose fore-arms are elevated and represented as holding a fan B behind the head C. The bust is represented as that of a woman wearing a dress with a low neck and no sleeves and having a chain about the neck.

What I claim is—
The design for a buckle front herein shown and described.

CHARLES R. HARRIS.
